UNITED STATES PATENT OFFICE.

CLARK E. RANNEY, OF TULSA, OKLAHOMA.

DERRICK.

Application filed December 24, 1925. Serial No. 77,527.

The invention relates to improvements in derricks, used particularly for the drilling of oil and gas wells, although, of course, applicable in any field where such a structure is found to have utility.

It is an object of the invention to provide a derrick of the type having wooden legs and girders, in which the girder is of rectangular form in cross-section, with its 10 elongated side in a horizontal plane and is adapted to be braced so that the entire derrick structure is adequately supported.

In the prior art it has been customary, in the construction of wooden derricks, to provide a girder of elongated rectangular form in cross-section with the elongated side in a vertical plane. With these structures, it has been impossible to adequately brace or reinforce the girders against bending in a 20 horizontal plane as brace rods cannot be employed to extend through the interior of the derrick as such rods would interfere with the operation of the drilling tool, and naturally it is not feasible to brace these 25 girders by supports extraneous of and located exteriorly of the derrick. Naturally, this practice has led to the use of girders of material dimensions because from an engineering standpoint no girder will stand any 30 compression greater than the compression that can be resisted by the thin portion of the girder. These girders have therefore been of greater dimensions than is necessary because of the absence of any adequate means 35 to reinforce the thin portion of the girder.

The present invention broadly comprehends the provision of a derrick in which a girder of a minimum size is employed in which the elongated side of the girder is 40 disposed in a horizontal plane so that this girder may be adequately braced from the derrick to permit its thinnest portion to stand just as much compression strain as the thickest portion thereof. These girders 45 are braced by devices attached to the leg braces of the derrick so as to prevent strains and stresses placed on the derrick from bending the thin portion of each horizontal girder.

50 The invention further comprehends a novel means for securing the ends of the girders to the legs of the derrick.

In the accompanying drawings,

Fig. 1 represents a view of the derrick as 55 assembled;

Fig. 2 is a detailed view of the supporting means for the ends of the girders,

Fig. 3 is a detailed view of the girder with its supporting braces, and

Fig. 4 is a sectional view of the apparatus. 60
Fig. 5 is a modified form.

Referring now more particularly to the drawings, wherein like reference characters indicate corresponding parts, the numeral 1 designates the supporting legs of the derrick. These legs are constructed from wooden beams of the desired thickness, the ends of the adjacent beams being secured together in any approved manner. As is customary in derricks of this structure, these beams converge as they extend from the base of the derrick, and at their upper ends support the usual mechanism around which the operating devices for the drill or casing lines pass. At one side of the derrick there is the usual calf wheel, while on the opposite side thereof the usual bull wheel is provided.

For supporting the legs 1, there is provided a plurality of girders 2. As shown in detail in Figs. 3 and 4, these girders are of elongated rectangular form in cross-section with their elongated sides disposed in a horizontal plane. With the standard form

of derrick, the girders are of 3 x 10 inches in cross-sectional area. It will be observed that the elongated or 10 inch side of the girder is disposed in a horizontal plane. This is of great importance for reasons as will hereinafter appear. The girders are supported to the legs 1 of the derrick. The supporting means for each girder is the same, and a description of one will suffice for all. As

shown in Fig. 2, each support comprises a bracket 3 which is a metal casting or stamping. It is of angular formation so as to fit two sides of the leg 1. That portion of the bracket fitting each side of the leg is provided with upper and lower flanges 4

separated a sufficient distance to receive therebetween the girder 2. The upper flange of one of the brackets is struck up to provide the ear 5 having a suitable bolt receiving opening therein, while the opposite side of the adjoining bracket is likewise provided with a struck up ear 6 for a similar fastening bolt. The flanges of the brackets are provided with aligned openings 8

through which retaining bolts pass to secure the girders in position. 100
105
110

An angle corner plate 9 fits around two sides of the leg 1 and serves to assist in uniting the bracket 3 to the leg and to also provide means by which brace rods may extend from one leg to another. Fastening bolts 11 pass through the struck up ears 5 in the flange members of the brackets 4 and pass through the supporting legs of the derrick and the corner plate 9. This serves to retain the assembly in position. Fastening bolts also enter the openings 8 in the flanges of the brackets to unite the girths to said brackets. The angle corner plates also have the openings 13 therein receiving the turned ends of brace rods 14 that extend between the corner posts 1 of the derrick as shown in Fig. 1. These brace rods are provided with turn buckles 14' by which they may be tightened and extend diagonally between the corner posts intersecting at a point substantially intermediate a pair of said corner posts. These rods are constructed of metal of $\frac{7}{8}$ inch in diameter more or less and serve to very adequately support the legs of the brace.

It will, of course, be appreciated that a girth is only as strong as its weakest section or part. The girths 2, as shown, are preferably formed of timber 3 x 10 inches in cross-section. The elongated portion of the girth will, of course, stand a substantial amount of compression. In order to make the thin portion of the girth stand an equal amount of compression, that is, the side thereof that is three inches in diameter, I have provided bracing means for this portion of the girth so that the compression will not serve to bend it. This permits the use of a girth of a minimum thickness, making the scaffold light in structure and inexpensive to manufacture. As shown in Fig. 4, a U-bolt 15 fits around each girth 2. This U-bolt preferably engages the girth at a point near its center. Each U-bolt is retained in position by a washer 16 and nuts 17. It will be understood that each girth has a supporting brace, and inasmuch as each girth is the same in construction a description of one will suffice for all.

One of the horizontal legs of each U-bolt is formed with a loop as indicated by the reference character 18 intermediate its end to receive the girth brace 19. This brace is constructed from metal, preferably metal tubing, having a flat end 20 which is fitted over the U-bolt and engages the portion 18 thereof. The upper end of each brace is secured to the leg supporting or bracing irons at the point at which a pair of said irons intersect. The brace is secured to said supporting irons or leg braces by a U-bolt 22 which encircles said supporting irons or braces 14 at their point of intersection, the legs of the U-bolt passing through openings 65 in the flattened end 23 of the brace which

is secured to the U-bolt by the nuts 24. It is therefore apparent that the brace is adequately supported by the heavy bracing or supporting rods 14 extending between the legs 1 and that this brace in turn supports the thin portion of the girth 2 so that compression will not bend this girth at its weakest point. It will be furthermore appreciated that by using the brace in this manner it does not interfere in any way with the operation of the tool and that its use permits a wooden girth of a minimum size to be employed which will have a strength at least equal to a substantially larger square girth, or a girth of a much greater size and cost.

In Figure 5 of the drawings, I have shown a slightly modified form of the invention in which a U-bolt 25 passes through an opening in the lower flattened end of the supporting brace, the U-bolt then passing through suitable holes in the girth 2. This U-bolt is secured in position by the nuts 26. Obviously, the upper end of the brace in this modified form engages the bracing irons or rods 14 of the derrick.

Having thus described the invention, what I claim is:

1. In a derrick, the combination with suitable legs, of bracing devices extending between the adjacent legs, girths of elongated rectangular form in cross-section connected with said legs, said girths having their elongated sides in a horizontal plane.

2. In a derrick, the combination with suitable legs, of bracing devices extending between the adjacent legs, girths of elongated rectangular form in cross-section connected with said legs, said girths having their elongated sides in a horizontal plane, and bracing elements connected with said bracing devices and said girths to brace the vertical sides of said girths.

3. In a derrick, the combination with suitable legs, bracing devices interposed between said legs, girths extending between said legs, each girth being of elongated rectangular form in cross-section, with the elongated side thereof in a horizontal plane, and bracing means for each girth connected with said bracing devices and with the girth to prevent a vertical bending of the girths.

4. In a derrick, the combination with suitable legs, bracing devices extending between spaced adjacent legs, girths of elongated rectangular form having relatively short and long sides in cross section connected with said legs with the long side of each girth disposed substantially in a horizontal plane, and bracing elements connecting said girths with said bracing devices.

In testimony whereof I affix my signature:

CLARK E. RANNEY.
